[57] CLAIM

The ornamental design for a snorkel face mask, as shown and described.

DESCRIPTION

FIG. 1 is a front and left side perspective view of a snorkel face mask showing my new design, the portion of the figure shown in broken lines representing a user's face and forming no part of the claimed design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
The lower strap is shown detached at one end in FIGS. 3 and 5.

FIG. 1

FIG. 2

FIG. 4
